(57) **CLAIM**

The ornamental design for a pistol slide as shown and described.

DESCRIPTION

FIG. 1 is a left, front, perspective view of a pistol slide showing our new design;

FIG. 2 is a right, rear, perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The evenly spaced broken lines depict portions of the pistol slide and environment of a pistol that form no part of the claimed design. The dot-dot-dash broken lines depict a symbolic break that form no part of the claimed design. The broken symbolic break lines and the area between the lines forms no part of the claimed design.
